Des. 198,052
Patented Apr. 21, 1964

198,052

PAIR OF SUNGLASSES OR THE LIKE

Albert C. Pettit, Hudson, Mass., assignor to Foster Grant Co., Inc., Leominster, Mass.

Filed Jan. 17, 1963, Ser. No. 73,216

Term of patent 14 years

(Cl. D57—1)

I claim:

The ornamental design for a pair of sunglasses or the like, substantially as shown.
